BROADLOOM EXHIBITOR

Victor Borevitz, San Diego, Calif.

Application June 10, 1941, Serial No. 397,397

10 Claims. (Cl. 242—55.3)

My invention relates to a broadloom exhibitor, more particularly an exhibitor for supporting and exhibiting broadloom rug material in rolled form, and the objects of my invention are:

First, to provide a broadloom exhibitor of this class in which broadloom material is supported in rolled form on revolvably mounted spools and in which geared operating means is provided for ease and efficiency in the revoluble operation of said spools;

Second, to provide a broadloom exhibitor of this class with angularly disposed bearing slots in which the broadloom supporting spools are readily removably supported;

Third, to provide a broadloom exhibitor of this class in which an elevating mechanism is provided for use in raising heavy rolls of broadloom materials to various positions relatively with the spool supporting bearing slots in the frame members of my broadloom exhibitor;

Fourth, to provide a broadloom exhibitor of this class with geared operating handle means for use in cooperative relation with both the broadloom supporting spools and the elevator mechanism of my broadloom exhibitor;

Fifth, to provide a broadloom exhibitor of this class in which latch means is arranged in cooperative relation with the spool operating gear of each of the broadloom supporting spools of my broadloom exhibitor for holding said spools in certain position;

Sixth, to provide a novel broadloom exhibitor of this class;

Seventh, to provide a broadloom exhibitor of this class in which the elevator mechanism is used in cooperative relation with both of the substantially vertical rows of broadloom supporting spools at opposite sides of my broadloom exhibitor;

Eighth, to provide a broadloom exhibitor of this class in which gravitational attraction of the loaded broadloom supporting spool helps to position the bearing portions of said spool in angularly inclined slotted bearing portions of my broadloom exhibitor as said spools are released by the elevator mechanism thereof; and

Ninth, to provide a broadloom exhibitor of this class which is very simple and economical of construction, efficient in its action and which will not readily deteriorate or get out of order.

With these and other objects in view as will appear hereinafter, my invention consists of certain novel features of construction, combination and arrangement of parts and portions as will be hereinafter described in detail and particularly

set forth in the appended claims, reference being had to the accompanying drawings and to the characters of reference thereon which form a part of this application in which:

Figure 1 is a fragmentary side elevational view of my broadloom exhibitor, showing portions broken away to facilitate the illustration; Fig. 2 is a transverse sectional view thereof taken from the line 2—2 of Fig. 1 showing varying positions

10 of parts and portions by dash lines; Fig. 3 is a fragmentary perspective detail view of one of the gear latch members in cooperative relation with one of the spool operating gears, fragmentary portions of the end frame member and spool supporting frame member being shown in section; Fig. 4 is a fragmentary end elevational view of my broadloom exhibitor; Fig. 5 is a fragmentary end elevational

20 view of my broadloom exhibitor showing a large roll of broadloom material being elevated into position and Fig. 6 is a fragmentary perspective view of the operating handle of my broadloom exhibitor in its operative relation with the operating handle gear and one of the spool operating gears in mesh therewith, a fragmentary portion of one of the end frame members and spool supporting frame member being shown in section; portions of the operating handle being shown broken away and in section.

Similar characters of reference refer to similar parts and portions throughout the several views of the drawings:

The end frame members 1 and 2, spool supporting frame members 3 and 4, broadloom supporting spools 5, 6, 7 and 8, frame edge cover members 9 and 10, operating handle 11, operating handle gear 12, spool operating gears 13, 14, 15 and 16, top member 17, bottom member 18, gear latch members 19, elevator shaft 20, elevator shaft operating gear 21, elevator chains 22 and 23, elevator latch members 24 and 25, chain supporting rollers 26, pulleys 27 and 28, pulley supporting members 29 and 30 and the brackets 31 and 32 constitute the principal parts and portions of my broadloom exhibitor.

The end frame members 1 and 2 form the opposite ends of my broadloom exhibitor. The end frame member 1, as shown in Fig. 4 of the drawings is a flat plate-like member preferably made of wood but which may be made of any suitable material, as desired. This end frame member 1 is provided with two rows of holes, 1a and 1b. These holes 1a and 1b are arranged to receive operating handle gear 12 and the shank portion

11a of the operating handle 11, as shown best in Fig. 6 of the drawings. These holes 1a and 1b are so arranged that the operating handle gear 12 when inserted therein may be in meshed relation with the gear teeth of one of the spool operating gears 13, 14, 15 or 16, as shown best in Fig. 2 of the drawings.

It will be here noted that the spool supporting frame members 3 and 4 are in connected relation with the end frame members 1 and 2 and are substantially co-extensive therewith. The spool supporting frame member 3 is provided with holes 3a and 3b which align with the holes 1a and 1b of the end frame member 1, as shown best in Fig. 6 of the drawings. The end frame member 1 is also provided with rows of holes 1c and 1d. These holes 1c and 1d are arranged to receive the gear latch members 19, as shown best in Fig. 3 of the drawings.

Positioned in the spool supporting frame member 3 and in alignment with the rows of holes 1c and 1d are the rows of holes 3c and 3d. As shown in Fig. 2 of the drawings, these holes 3c and 3d are in alignment with the gear teeth of the spool operating gears 13, 14 and 15. Positioned in the holes 1c and 1d in alignment with the holes 3c and 3d are the gear latch members 19 which are operatively engageable with the gear teeth of the spool operating gears 13, 14, 15 and 16. Each of these gear latch members 19 is provided with a shank portion 19a which extends through the end frame member 1 and the spool supporting frame member 3, shown best in Fig. 3 of the drawings. These gear latch members 19 are each provided with a handle portion 19b on one end and a semi-circular in cross section latch portion 19c on the opposite end from the handle portion 19b, all as shown best in Fig. 3 of the drawings.

The end frame member 2 is a substantially flat plate-like member having similar outline shape to the end frame member 1. This end frame member 2 does not have any openings therein as does the end frame member 1. Each of the spool supporting frame members 3 and 4 is provided with upwardly inclined slotted bearing portions which are open at the outer opposite edges of said spool supporting frame members 3 and 4, as shown best in Figs. 1 and 2 of the drawings. These slotted bearing portions 3e and 3f are each provided with arcuate portions 3g at their inner ends arranged to receive the bearing end portions of the broadloom supporting spools 5, 6, 7 and 8, as shown best in Figs. 1 and 2 of the drawings.

Secured to the opposite edges of the end frame members 1 and 2 by means of the hinges 9a and 10a are the frame edge cover members 9 and 10. These frame edge cover members 9 and 10 are flat plate-like members preferably made of wood and are arranged to cover the edges of the spool supporting frame members 3 and 4 at the open end portions of the slotted bearing portions 3e and 3f, all as shown best in Figs. 1 and 2 of the drawings. These frame edge cover members 9 and 10 are arranged to be pivotally shifted away from the edge portions of the spool supporting frame members 3 and 4 when inserting one of the broadloom supporting spools 5, 6, 7 or 8 into the spool supporting frame members 3 and 4.

The operating handle 11 is preferably circular in form, as shown in Figs. 4 and 6 of the drawings and this operating handle 11 is connected with the operating handle gear 12 by means of the shaft 11b, as shown best in Fig. 6 of the

drawings. This shaft 11b is revolvably mounted in the shank portion 11a and this shank portion 11a is provided with an enlarged end portion 11c arranged to form an abutment at the outer side 5 of the end frame member 1, as indicated in Fig. 1 of the drawings.

The broadloom supporting spools 5, 6, 7 and 8 are substantially identical in form and therefore the broadloom supporting spool 5 will be described in detail. This broadloom supporting spool 5 is provided with a central tubular shaft member 5a, the opposite ends of which are arranged to engage the slotted bearing portions 3e or 3f of the spool supporting frame members 3 and 4.

Secured on the shaft member 5a near its one end is the spool operating gear 13. This spool operating gear 13 is substantially identical to the spool operating gears 14, 15 and 16 which are conventional spur gears. Positioned on the shaft member 5a adjacent the spool operating gear 13 is a disc-shaped end member 5b which is substantially identical in form to the disc-shaped member 5c positioned on and near the opposite end of the shaft 5a, as shown best in Figs. 1 and 2 of the drawings. Secured on the inner sides of each of these disc-like members 5b and 5c are smaller disc-shaped plates 5d and 5e. Secured on these smaller disc-shaped plates 5d and 30 5e are slats 5f. These slats 5f extend longitudinally and in parallel relation with the shaft 5a and are connected at their opposite ends with the disc-shaped members 5d and 5e, as shown best in Figs. 1 and 2 of the drawings.

As shown in Figs. 1 and 2 of the drawings, the elevator shaft 20 is journalled at its opposite ends in the spool supporting frame members 3 and 4 at substantially the middle thereof and secured on this elevator shaft 20 adjacent the spool supporting frame member 3 is the elevator shaft operating gear 21. This gear 21 is substantially the same diameter and form as the spool operating gears 13, 14, 15 and 16. Positioned in the spool supporting frame member 3 and the end frame member 1 is an opening 21a, which opening 21a is outwardly of the periphery of the elevator operating gear 21 and this opening 21a is arranged to receive the operating handle gear 12 and is arranged to guide the same into mesh with the elevator operating gear 21, as shown best in Fig. 4 of the drawings.

Pivots mounted at opposite sides of the elevator operating gear 21 are the elevator latch members 24 and 25. These elevator latch members 24 and 25 are arranged to be pivotally shifted by the semi-circular in cross section latch portions 19c of the gear latch members 19, all as shown best in Fig. 2 of the drawings. As shown in Fig. 4 of the drawings the gear latch members 19 extend through the end frame member 1 and the spool supporting frame member 3 in cooperative relation with the elevator latch members 24 and 25 at opposite sides of the elevator operating gear 21.

Secured on the elevator shaft 20 near its opposite ends are the elevator chains 22 and 23. These elevator chains 22 and 23 extend upwardly in substantially vertical relation at the middle portion of my broadloom exhibitor, as shown best in Figs. 1, 2 and 5 of the drawings. As shown by dash lines in Fig. 2 of the drawings, these elevator chains 22 and 23 extend through openings 22a in the top member 17. It will be here noted that the top member 17 is supported at its opposite ends on the end frame members

1 and 2 and that the end frame members 1 and 2 are interconnected at their lower ends by means of the bottom member 18. The elevator chains 22 and 23 extend upwardly through the openings 22a in the top member 17 and extend over the chain supporting rollers 26 and horizontally therefrom to the pulleys 27 and 28, as shown best in Figs. 1, 2 and 5 of the drawings.

The pulleys 27 and 28 are substantially identical in form and the supporting mechanism for each of these pulleys 27 and 28 is substantially identical. Therefore the pulley 28 together with its supporting mechanism will be described in detail.

The pulley 28 is supported on the extending end of the tubular telescopic pulley supporting member 29, as shown best in Figs. 1, 2 and 5 of the drawings. This pulley supporting member 29 is reciprocally mounted in the pulley supporting member 30 and the pulley supporting member 30 is supported near its opposite ends on the top member 17 by means of the brackets 31 and 32. The brackets 31 and 32 are each provided with set screws 31a which are arranged to fix the pulley supporting member 29 in certain stationary relation with the pulley supporting member 30, all as shown best in Figs. 1, 2 and 5 of the drawings.

As shown in Fig. 5 of the drawings, the elevator chain 23 extends upwardly from the elevator shaft 20 over the roller 26 and horizontally to the pulley 28 over the same and downwardly into connection with a roll A of broadloom material.

The operation of my broadloom exhibitor is substantially as follows:

When it is desired to position broadloom material upon one of the broadloom supporting spools 5, 6, 7 or 8, one end of the piece of broadloom material is secured by tacks or otherwise on the longitudinally disposed slats thereof and the operating handle, together with the operating handle gear 12, is arranged in cooperative relation with one of the holes 1a or 1b whereby the operating handle gear 12 is in meshed relation with one of the spool operating gears 13, 14, 15 or 16 in connection with the broadloom supporting spool to be operated. The operating handle 11 is then revolved and the operating handle gear 12 revolves the broadloom supporting spool in connection with the spool operating gear in mesh therewith. Thus the broadloom material is positioned on the broadloom supporting spool.

When it is desired to change the position of a loaded broadloom supporting spool, as shown in Fig. 5 of the drawings, a strap A' is positioned around each opposite end of the roll A of broadloom material and the elevator chains 22 and 23 are connected therewith. The operating handle 11 in connection with the operating handle gear 12 is arranged to operate the elevator operating gear 21 on the elevator shaft 20 which is arranged to enroll the elevator chains 22 and 23 thereon.

It will be here noted that the slotted bearing portions 3e and 3f in the spool supporting frame members 3 and 4 are arranged to provide various spaced relation of the broadloom supporting spools 5, 6, 7 and 8 depending upon the diameter thereof when loaded with broadloom material. The gear latch members 19 are revolvably shifted into engagement with the spool operating gears 13, 14, 15 and 16 and the semi-circular in cross section latch portions 19c of these gear latch

members 19 engage the gear teeth of the spool operating gears, as shown best in Fig. 3 of the drawings. When turned a quarter of a revolution, these semi-circular in cross section latch portions 19c are disengaged from the gear teeth of the spool operating gears 13, 14, 15 and 16, as desired. The semi-circular in cross section latch portions 19c of the gear latch members 19 which engage the elevator latch members 24 and 25 act as cams for pivoting the elevator latch members 24 and 25 into and out of engagement with the elevator shaft operating gear 21 for holding the same in fixed position against revoluble operation in either direction, as desired.

As shown in Fig. 5 of the drawings, the pulley 28 supported on the pulley supporting member 29 may be extended outwardly into any position as desired depending upon the diameter of the roll of broadloom material being supported on the elevator chains 22 and 23. When the roll A of broadloom material is elevated to the proper elevated position relatively with the slotted bearing portions 3e and 3f in the spool supporting frame members 3 and 4, the pulley supporting member 29 may be telescoped into the pulley supporting members 30 shifting the roll A of broadloom material toward the open portion of said slotted bearing portions 3e and 3f for positioning opposite ends of the broadloom supporting spool shaft in said slotted bearing portions 3e or 3f, as desired.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a broadloom exhibitor of the class described, the combination of spaced spool supporting frame members provided with open inwardly and downwardly extending slotted bearing portions at their edges, broadloom supporting spools having shaft bearing portions positioned in said slotted bearing portions, said spool supporting frame members having rows of openings therein parallel with said slotted bearing portions, a spur gear supported on each of said broadloom supporting spools near one end thereof and a handle provided with a pinion gear revolvably positioned in one of said openings in cooperative relation with one of said spur gears.

2. In a broadloom exhibitor of the class described, the combination of spaced spool supporting frame members provided with open inwardly and downwardly extending slotted bearing portions at their edges, broadloom supporting spools having shaft bearing portions positioned in said slotted bearing portions, said spool supporting frame members having rows of openings therein parallel with said slotted bearing portions, a spur gear supported on each of said broadloom supporting spools near one end thereof, a handle provided with a pinion gear revolvably positioned in one of said openings in cooperative relation with one of said spur gears, and latch means in cooperative relation with said spur gears.

3. In a broadloom exhibitor of the class described, the combination of spaced spool support-

ing frame members provided with open inwardly and downwardly extending slotted bearing portions at their edges, broadloom supporting spools having shaft bearing portions positioned in said slotted bearing portions, said spool supporting frame members having rows of openings therein parallel with said slotted bearing portions, a spur gear supported on each of said broadloom supporting spools near one end thereof, a handle provided with a pinion gear revolvably positioned in one of said openings in cooperative relation with one of said spur gears, latch means in cooperative relation with said spur gears, and elevator means arranged to lift said broadloom supporting spools relatively with said spool supporting frame members.

4. In a broadloom exhibitor of the class described, the combination of spaced spool supporting frame members, broadloom supporting spools revolvably mounted in connection with said spool supporting frame members, a spur gear in connection with each of said broadloom supporting spools, said spool supporting frame members provided with openings therein near each of said gears and an operating handle with a pinion gear in connection therewith revolvably positioned in one of said openings and in meshed relation with one of said spur gears.

5. In a broadloom exhibitor of the class described, the combination of spaced spool supporting frame members, broadloom supporting spools revolvably mounted in connection with said spool supporting frame members, a spur gear in connection with each of said broadloom supporting spools, said spool supporting frame members provided with openings therein near each of said gears, an operating handle with a pinion gear in connection therewith revolvably positioned in one of said openings and in meshed relation with one of said spur gears, and latch means in operative relation with said spur gears.

6. In a broadloom exhibitor of the class described, the combination of spaced spool supporting frame members, broadloom supporting spools revolvably mounted in connection with said spool supporting frame members, a spur gear in connection with each of said broadloom supporting spools, said spool supporting frame members provided with openings therein near each of said gears, an operating handle with a pinion gear in connection therewith revolvably positioned in one of said openings and in meshed relation with one of said spur gears, and latch means in operative relation with said spur gears, said latch means including a revolvable shaft having a semi-circular in cross section end latch portion engageable with the teeth of said spur gears.

7. In a broadloom exhibitor of the class described, the combination of spaced spool support-

ing frame members, broadloom supporting spools revolvably mounted in connection with said spool supporting frame members, a spur gear in connection with each of said broadloom supporting spools, said spool supporting frame members provided with openings therein near each of said gears, an operating handle with a pinion gear in connection therewith revolvably positioned in one of said openings and in meshed relation with one of said spur gears, said operating handle having said pinion gear rigidly connected therewith and a shank portion in revolvable relation with said handle arranged to fit in said openings.

8. In a broadloom exhibitor of the class described, the combination of spaced spool supporting frame members, broadloom supporting spools revolvably mounted in connection with said spool supporting frame members, a spur gear in connection with each of said broadloom supporting spools, said spool supporting frame members provided with openings therein near each of said gears, an operating handle with a pinion gear in connection therewith revolvably positioned in one of said openings and in meshed relation with one of said spur gears, said operating handle having said pinion gear rigidly connected therewith, and a shank portion in revolvable relation with said handle arranged to fit in said openings, each of said broadloom supporting spools provided with longitudinally disposed slats and disc-shaped end members.

9. In a broadloom exhibitor of the class described, the combination of spaced spool supporting frame members, broadloom supporting spools revolvably mounted in connection with said spool supporting frame members, a spur gear in connection with each of said broadloom supporting spools, said spool supporting frame members provided with openings therein near each of said gears, an operating handle with a pinion gear in connection therewith revolvably positioned in one of said openings and in meshed relation with one of said spur gears, and elevator means in connection with said spool supporting members and arranged to elevate said spools relatively therewith.

10. In a broadloom exhibitor of the class described, the combination of two substantially vertical rows of broadloom supporting spools, spool supporting frame members at opposite ends thereof, an elevator shaft parallel with and between said rows of broadloom supporting spools, rollers stationarily mounted above said elevator shaft, pulleys outwardly of said rollers and shiftable therewith and elevator chains connected with said elevator shaft and extending over said rollers and said pulleys above said substantially vertical rows of broadloom supporting spools.

VICTOR BOREVITZ.
